KEY HOLDER

Evan William Pritchard, Cleveland, Ohio

Application April 11, 1933. Serial No. 665,577

1 Claim. (Cl. 59—97)

The present invention relates to new and useful improvements in holders for keys, particularly automobile, garage and house keys, and has for one of its important objects to provide, in a 5 manner as hereinafter set forth, a holder of this character embodying a novel construction, combination and arrangement of parts through the medium of which rattling of the keys will be prevented as well as swinging of the holder 10 against the instrument board of an automobile when suspended from a key which is inserted in an ignition switch.

Another very important object of the invention is to provide a key holder of the aforementioned character embodying a construction which is such that the keys may be easily attached and detached when desired.

Other objects of the invention are to provide a key holder of the character described which 20 will be simple in construction, strong, durable, highly efficient and reliable in use, compact, attractive in appearance and which may be manufactured at low cost.

All of the foregoing and still further objects 25 and advantages of the invention will become apparent from a study of the following specification, taken in connection with the accompanying drawing wherein like characters of reference designate corresponding parts throughout the several 30 views, and wherein:—

Figure 1 is a view in side elevation of a key holder constructed in accordance with the present invention.

Figure 2 is a plan view of the blank from which 35 the holder is formed.

Figure 3 is a view in vertical transverse section, taken substantially on the line 3—3 of Figure 1.

Figure 4 is a top plan view of the key holder.

Figure 5 is a view in longitudinal horizontal 40 section through one end portion of the holder.

Referring now to the drawing in detail, it will be seen that the embodiment of the present invention which has been illustrated is formed from a blank 1 which comprises a single sheet of resilient material. The holder includes pairs of spaced, opposed plates 2 and 3 which are connected with each other by a comparatively short, integral web 4, thus leaving the end portions of the outer plates 3 free.

50 The inner plates 2 are opposed, side abutting engagement with each other, the blank 1 being folded upon itself on its longitudinal center, as indicated at 5 in Figure 2 of the drawing. It will thus be seen that a holder comprising a pair 55 of key compartments or chambers 6 has been pro-

vided, said chambers being open on one side for the reception of the keys and being closed on the opposite side by the connecting webs 4 of the spaced plates 2 and 3.

The free end portions of the outer plates 3 60 of the holder are inwardly offset, as at 7 for frictionally gripping the heads 8 of the keys 9. Beveled or inclined portions 10 connect the inwardly offset end portions 7 with the main body portions of the side plates 3. Stamped in the 65 inwardly offset end portions 7 of the plates 3 are studs or teats 11 which engage in the usual openings in the heads 8 of the keys 9, as clearly seen in Figure 5 of the drawing, thus securing the keys to the holder for swinging movement into and out of the chambers 6.

It will thus be seen that a key holder has been provided wherein the chambers 6 are considerably greater in width than the thickness of the keys but wherein the space between the inwardly offset end portions 7 of the side plates 3 and the corresponding portions of the inner side plates 2 is less than the thickness of the keys, thus assuring a frictional grip on the head portions 8 of the keys which will be sufficient to secure the 80 keys and the holder against idle swinging movement relative to each other. As will be apparent, the keys are swung into and out of the chambers 6, said keys rotating or swinging on the studs or teats 11. As will also be apparent, the keys 85 may be readily detached from the holder by exerting sufficient pull thereon to disengage the studs or teats 11 from the openings in said keys. The keys may be conveniently engaged in the holder by inserting the head portions 8 in the 90 chambers 6 and then forcing said head portions between the inwardly offset end portions 7 of the outer plates 3 and the corresponding end portions of the inner plates 2 until the studs or teats 11 snap into the openings in the key heads, the inclined or beveled shoulders or connecting portions 10 facilitating this operation.

It is believed that the many advantages of a key holder constructed in accordance with the present invention will be readily understood, and 100 although the preferred embodiment of the invention is as illustrated and described, it is to be understood that changes in the details of construction and in the combination and arrangement of parts may be resorted to which will fall within 105 the scope of the invention as claimed.

What is claimed is:—

A key holder comprising a pair of integral, opposed, side abutting inner plates connected with each other along one longitudinal edge, a pair of 110

outer plates arranged in spaced, opposed relation to the inner plates for providing key receiving chambers therebetween, integral webs connecting the outer plates with the other longitudinal edges 5 of the inner plates, and means for frictionally gripping the keys between the end portions of the inner and outer plates, the chambers being of a width greater than the thickness of the keys, the outer plates including inwardly inclined portions 10 terminating in inwardly offset end portions

paralleling the corresponding portions of the inner plates in spaced relation thereto, the space between the end portions of the inner and outer plates being normally less than the thickness of the keys, and studs projecting inwardly from the 80 inwardly offset end portions of the outer plates for engagement with the keys, said plates, the connecting webs and the studs being formed from a single piece of resilient metal.
